UNITED STATES PATENT OFFICE

140,555

DESIGN FOR A GAME BOARD

Robert Ruffin, New Orleans, La.

Application October 26, 1944, Serial No. 115,994

Term of patent 7 years

(Cl. D34—5)

To all whom it may concern:

Be it known that I, Robert Ruffin, a citizen of the United States, residing at New Orleans, in the Parish of Orleans and State of Louisiana, have invented a new, original, and ornamental Design for a Game Board, of which the following is a specification, reference being had to the accompanying drawing, forming part thereof.

I claim:

The ornamental design for a game board, as shown.

ROBERT RUFFIN.
